(57) CLAIM

The ornamental design for a cosmetic container, as shown and described.

DESCRIPTION

FIG. 1 is a top, front and right side perspective view of a first embodiment of our new design for a cosmetic container; FIG. 2 is a front elevation view of the cosmetic container shown in FIG. 1, the rear elevation view being identical thereto;

FIG. 3 is a right side elevation view of the cosmetic container shown in FIG. 1, the left side elevation view being identical thereto;

FIG. 4 is a top plan view of the cosmetic container shown in FIG. 1;

FIG. 5 is a bottom plan view of the cosmetic container shown in FIG. 1;

FIG. 6 is a top, front and right side perspective view of a second embodiment of our new design for a cosmetic container;

FIG. 7 is a front elevation view of the cosmetic container shown in FIG. 6, the rear elevation view being identical thereto;

FIG. 8 is a right side elevation view of the cosmetic container shown in FIG. 6, the left side elevation view being identical thereto;

FIG. 9 is a top plan view of the cosmetic container shown in FIG. 6; and,

FIG. 10 is a bottom plan view of the cosmetic container shown in FIG. 6.
